PILASTER BUILDING BLOCK

Frank K. Locke, Hudson, Mich., assignor to Stearns
Manufacturing Co., Inc., Flat Rock, Mich., a cor-
poration of Michigan

Filed Dec. 5, 1968, Ser. No. 14,808

Term of patent 14 years

Int. Cl. D25—01
U.S. Cl. D18—2

FIG. 1

FIG. 2

FIG. 3

FIG. 4

FIGURE 1 is a perspective view from an upper corner of the front of a pilaster building block embodying my inventive design;

FIGURE 2 is a top view thereof;

FIGURE 3 is a front view thereof; and

FIGURE 4 is a view of the end opposite to that shown in FIGURE 1.

I claim:

The ornamental design for a pilaster building block, as shown.
